COMBINED ELECTROMAGNETIC AND
THERMAL CIRCUIT BREAKER

William E. Stilwell, Jr., Cincinnati, Ohio, assignor to John B. Pierce Foundation, New York, N. Y., a corporation of New York

Application December 5, 1942, Serial No. 467,919

5 Claims. (Cl. 200—88)

1

This invention relates to electric circuit breakers.

It is an object of the invention to provide an electric circuit breaker of small size and light weight, capable of efficiently breaking high amperage circuits at high speed, and adapted to be subjected to overload conditions without physical damage or change of calibration.

It is an object of the invention to provide a circuit breaker incorporating means for breaking the circuit under overload conditions of predetermined magnitude.

It is an object of the invention to provide a circuit breaker having ambient temperature compensation.

It is an object of the invention to provide a circuit breaker having improved operating characteristics when used as a remote control switch or as an overload protective device.

It is an object of the invention to provide a circuit breaker having improved means to minimize the effect of arcing at the load line contacts, thereby to increase the life of such contacts.

It is an object of the invention to provide a circuit breaker which will not accidentally trip under conditions of abnormal vibration or the inertia effect of sudden changes in direction, such as might be experienced in aircraft.

These and other objects and advantages will more fully appear from an examination of the drawings, in which

Fig. 1 is a side elevation of one form of circuit breaker embodying my invention;

Fig. 2 is an enlarged elevation, in vertical central section, of the circuit breaker of Fig. 1, showing the load contacts in closed position;

Fig. 3 is a fragmentary elevation, in section, taken along lines 3—3 of Fig. 2;

Fig. 4 is a sectional plan view, taken on lines 4—4 of Fig. 3;

Fig. 5 is a view similar to Fig. 2, showing the load circuit in open status;

Fig. 6 is a top plan view of the circuit breaker shown in Fig. 1;

Fig. 7 is a schematic wiring diagram for the circuit breaker of Fig. 1;

Fig. 8 is a side elevation of another embodiment of circuit breaker embodying the invention;

Figs. 9 and 10 are elevations, in vertical central section, of the circuit breaker of Fig. 8; Fig. 9 shows the load line contacts in closed circuit position, and Fig. 10 the contacts in open circuit position;

Fig. 11 is a horizontal section through lines

2

11—11 of Fig. 9, showing the arrangement of an arcing disc;

Fig. 12 is a wiring diagram for the embodiment of Fig. 8;

5 Fig. 13 is an elevation of another embodiment of my invention;

Figs. 14 and 16 are sectional elevations (Fig. 16 being fragmentary) taken on lines 14—14 of Fig. 13; in Fig. 14, the load circuit is closed, whereas in Fig. 16, the load circuit is open;

10 Fig. 15 is a plan section taken on lines 15—15 of Fig. 14; and

Fig. 17 is a schematic wiring diagram for the Fig. 13 embodiment.

15 In the embodiment illustrated in Figs. 1 through 6, my invention comprises members 20, 21 of aluminum or other light metallic material, inset into body members 22, 23 of electric insulation material, such as "Bakelite" or equivalent.

20 Within the hollow chamber afforded by such combination is an aluminum ring 24 having peripheral grooves 25, 26 in parallelism. A solenoid housing 27 finned for heat radiation, completes the principal body structure.

25 Except for ring 24, the stated body members may be of mating half-portions, whereby the respective elements may be fitted together and secured in any suitable manner.

In the base of solenoid housing 27 may be placed a block 28 of insulation material, to serve as a connection block for binding posts (not shown) of the control circuit.

30 Principal elements of the circuit breaker mechanism per se include load circuit contacts 30, 31 respectively, welded to the aluminum members 20, 21, a shorting bar 32 adapted to bridge the gap between said contacts 30, 31, see Fig. 2, and an arcing bridge-arm 33 having contacts 34, 35, see Fig. 4, for cooperation with fixed arcing contacts 36, 37 suitably connected into the circuit as shown in Fig. 7. The agency of connection of contacts 30, 31 into the load circuit may be the studs 38, 40 welded to housing members 20, 21, and carrying suitable cable-receiving lugs 41, 42.

35 Make and break of the load-line contacts is accomplished by remote control through a solenoid system and therewith associated toggle spring mechanism. The solenoid system includes coils 50, 51 suitably contained and positioned within housing 27, and so associated in the electrical circuit that coil 50, the "on" coil, is energized when the load circuit is to be closed, and coil 51, the "off" coil, is energized to open the load circuit, it being understood that the ener-

55

gization of the respective coils is momentary only.

Operatively associated with said coils is a magnetically responsive armature 52, suitably guided for movement under the influence of one or the other of such coils. Said armature carries a shaft 53, preferably non-magnetic, to the balled end of which is secured the shorting bar 32.

As illustrated in Fig. 2, an intermediate portion of shaft 53 is threaded to receive locking nuts 54, 55, between which is confined a toggle spring 56, most preferably of the type disclosed in my presently copending application Serial No. 441,382, filed May 1, 1942, now abandoned. A characteristic of such toggle spring is that it has two positions of stable equilibrium, represented by convex or concave form, and that the transition from one to the other of such positions is accomplished with great rapidity and force, and after an external "flipping" force has been applied for less than one half of the total distance traveled by a point at the center of said toggle spring during its throw. The periphery of said toggle spring is somewhat loosely confined within the groove 25 of ring 24.

Because of the "flipping" characteristics of toggle spring 56, only a momentary energization of the solenoid coils is necessary to move the armature 52 through a sufficient distance to cause the toggle spring 56 to complete its throw under the influence of its own internally generated forces.

Advantageously, engagement is made between shorting bar 32 and contacts 30, 31, prior to the full throw of spring 56, whereby the unexpected energy of such spring acts to maintain said engagement with continuing resilient pressure.

Protection against the damaging effects of arcing at the principal load-line contacts 30, 31 is afforded by the supplemental contacts 34, 35, 40 which respectively engage wedge-shaped fixed contacts 36, 37, the latter being carried by an insulator 60 inset into housing member 23. Said contacts 36, 37 are electrically connected to the respective aluminum housing members, and thereby to the electrical circuit, by the metal plates 61, 62 and the resistors 63, 64, respectively.

Arcing contact arm 33 is pivotally supported by a yoke 65 secured to insulating housing member 22, see Fig. 4. Disposed beneath said arm 33 and loosely surrounding shaft 53, which in turn passes freely through an opening in arm 33, is a sleeve 66 which rests upon a second double equilibrium point toggle spring 67, supported within the circumferential groove 26 in ring 24. Sleeve 66 abuts against the underface of arm 33, see Figs. 2 and 3.

Shaft 53 passes freely through toggle spring 67, and hence said toggle spring is not thrown by the down stroke of shaft 53.

Importantly, however, the arcing arm 33 is thrown downwardly by the impact of shorting bar 32 thereagainst, when said shorting bar is moving downwardly under the driving force of toggle spring 56 when said spring has been actuated by energization of the "off" solenoid 51.

The impact of shorting bar 32 against arm 33 after shorting bar 32 has itself attained a high velocity of movement, has two important advantages: it increases the speed of break of contacts 30, 31 with respect to contacts 36, 37, and it permits construction whereby said contacts 34, 35 may be tightly wedged against the fixed contacts to improve electrical connection therebetween. Accordingly, said fixed contacts 36, 37

may be of wedge formation, thicker at the top, as viewed in Fig. 4, than at the bottom. Contacts 34, 35 are secured to the ends of springable arm-portions of contact arm 33; and when arm 33 is driven upwardly under the combined efforts of toggle spring 56 and 67, acting through sleeve 66, the contacts 34, 35 move upwardly along contacts 36, 37, after initial engagement therewith, to an extent permitted by the resilience of such springable arm-portions. A wiping contact is thereby attained, keeping the respective contacts free of oxide formations, and continuously compensating for wear.

Over-load protection and ambient temperature compensation are obtained by the cooperating bi-metallic elements 70, 71, disposed in the head of the circuit breaker, see Fig. 2, within a chamber formed by a suitable cap 72 of molded plastic.

Bi-metallic element 70 is secured at one end to one of the aluminum housing elements, as 20, and when relatively cool, as is the circumstance when the current through the circuit breaker is a normal load current, remains in contact with the member 20. Under over-load condition the member 20, which provides the path of current to terminal stud 38, will experience a temperature rise and will transmit the increasing temperature to the bi-metallic element 70, which will warp upwardly in the direction of the contact 71. Under a sufficiently high temperature condition, the contacts 70, 71 will meet, and as shown in the wiring diagram, Fig. 7, will thereupon energize the "off" solenoid coil and cause the circuit breaker to be thrown into open circuit position. Because of the double equilibrium point of toggle spring 56, the circuit will remain open after the bi-metallic member 70 has cooled sufficiently to break contact with contact 71 and it will be necessary for the operator to close the circuit control switch 74, see Fig. 7, to re-energize the "on" solenoid coil to throw the circuit into closed position.

Compensation for ambient temperature is accomplished by making contact strip 71 also of bimetal and attaching it to a button 75 of aluminum or other metal having high heat conductivity which passes through the cap 72 and presents several finned radiation surfaces to the ambient temperature.

Said contact button 75 may be produced by forming said button with an elongated cylindrical shank 76 which passes through a suitable aperture in the housing 72 and then is upset to form a relatively large-area stud or plate 77 to which contact strip 71 is attached by means of the illustrated screw or equivalent.

The bi-metal of contact strip 71 is so arranged that when the circuit breaker is exposed to low temperatures, as may be experienced in aircraft at high altitudes, the contact strip is warped in the direction of contact strip 70, thereby necessitating a shorter travel or extent of warping of said strip 70 under the overload condition.

In the wiring diagram of Fig. 7, the switch 74 is schematically shown and is representative of any plurality of momentary contact switches located at any desired number of stations. The switch makes circuit through either the "on" contacts 76 or the "off" contact 71 and the respective "on" and "off" solenoid coils are actuated during the momentary closing of the control circuit.

It will be recalled that the arc-resisting contacts 34, 35 of the arcing arm 33 remain in engagement with the fixed contacts 36 and 37 for a

moment after the main contacts 30, 31, 32 have been opened; and it is only when said arc-resisting contacts have been opened that the load circuit L is in open status.

As is apparent from Fig. 7, when contact is made between the over-load and/or ambient temperature contacts 70, 71, the "off" solenoid coil 51 is energized, regardless of the fact that the control switch 74 may be in its normal, i. e., open circuit status, and hence the load circuit L is opened automatically in the circumstance of an over-load.

In the embodiments of Figs. 8 through 11, the housing may comprise half portions 100, 101 of equal size and shape but of opposite hand, said portions 100, 101 being of insulation material, and a metallic, preferably aluminum, coil housing 102, also of mating half portions keyed into a suitable formation in the bottom of the housing portions 100, 101 as shown in Fig. 9.

Confined within the coil housing 102, is a solenoid structure including opposed pole pieces 103, 104, between which and a central plate 105 are solenoid coils 106, 107, said coils being respectively the "on" coil and the "off" coil. A magnetic armature 108 to which is secured a desirably non-magnetic shaft 109 carries at its upper end a shorting bar 110, which may be of silver or equivalent and which makes or breaks with the load-line contacts 111, 112.

The prime force driving said shaft 109 upwardly or downwardly is the toggle spring 114 which may have the previously described double equilibrium characteristic and characteristic of full throw after an impulse of less than one-half of the distance of the throw engendered by the respective solenoid coils 106, 107.

The shorting bar 110 makes contact with the load contacts 111, 112 before the attainment of full throw position of the toggle spring 114, whereby said toggle spring maintains a positive resilient pressure on the load line contacts.

Protection against the effects of arcing is obtained by using a supplemental set of contacts 115, 116 in combination with a disc 117 preferably of spring silver secured to the shaft 109 immediately beneath the shorting bar 110.

Fig. 12 shows diagrammatically the circuit connections of the respective parts of the embodiment illustrated in Figs. 8 through 11, the circuit control switch 74 functioning with respect to the therein indicated circuits similarly as the circuit control switch 74 in the circuit diagram of Fig. 7.

As indicated in Fig. 9, the spring silver disc 117 is flexed when the principal load line contacts are closed. Hence the silver disc 117 remains in engagement with the contacts 115, 116 momentarily after the load line contacts have been broken, maintaining a closed circuit status during that brief interval. The rapidity with which the toggle spring 114 snaps from one to another of its positions of stable equilibrium effects a quick break at the arcing status. Such quick break and the wiping action of the silver disc 117 against the contacts 115, 116 materially lengthen the life of the arcing contacts.

Ambient and over-load protection is obtained by making the shorting bar 110 in a disk-like shape, with edge portions beaded inwardly as indicated in Figs. 9 and 10, and confining within the hollow of the shorting bar a bi-metallic member 118, desirably of a snap-spring formation and carrying at its center a contact button 120.

The bi-metallic snap spring 118 is influenced by the temperature of the shorting bar 110, and

as the temperature thereof rises under an over-load condition, the snap spring 118 will distort because of its bi-metallic structure until the interiorly generated forces are sufficient to cause it to snap abruptly from its concave form of Fig. 9 to a convex form in which its contact 120 engages with the contact 121 disposed in the head of the housing, as indicated in dash outline in Fig. 9.

In the embodiment of Figs. 13 through 16, the circuit breaker housing includes a plastic cap 200 and a substantially cylindrical aluminum body portion 201 screw threadedly secured thereto as shown in Fig. 14.

Within said aluminum body portion is a coil housing 202 containing solenoid coils 203, 203a, respectively, for individual connection into the electric circuit, Fig. 17, and respectively acting upon a magnetic armature 204.

To one end of armature 204 is secured a shaft 205, carrying at its upper end a bridging contact 206 having a relatively large inturned flange 207 which functions as a contacting surface between the load line contacts 208, 210.

The bridging contact 206 is brought into or out of engagement with contacts 208, 210 by a toggle spring 211, said toggle spring being confined within members 212, 214. Movement of the bridging contact is initiated by the "on" solenoid 203 or the "off" solenoid 203a; said solenoids are momentarily energized and impart to the toggle spring 211 the initial impulse effective to cause said spring to throw through its full travel.

In the base portion of housing 201, insulated therefrom within an open-ended and open bottom insulating housing 209, is an arcing contact arm 215, pivotally supported as shown in Fig. 15, and carrying at one end a contact 216 which makes or breaks with a fixed contact 217. Said contacts 216, 217 collectively form means for protecting the load line contacts 208, 210 from arcing, by maintaining the load circuit in closed status after the bridging contact 206 has been moved downwardly from the contacts 208, 210 under the conjoint drive of "off" solenoid 203a and toggle spring 211.

The arm member 215 is operated by means of a shaft 218 secured to the armature 204; a transverse bar at the end of shaft 218 is passed through a suitable keyhole slot in the arm 215 to provide a relatively loose connection therewith.

When the armature 204 moves upwardly to bring the shorting device 206 into engagement with the terminals 208, 210, shaft 218 rotates the arm 215 about its pivot. The length of the stroke of shaft 218 is such that the contacts 216, 217 are engaged prior to the full stroke movement of shaft 218, and the continued movement of said shaft 218 flexes arm 215, see Fig. 14. On the downstroke of shaft 218, when the circuit breaker is being activated to open-circuit position, the contacts 216, 217 remain in engagement after bridging contact 206 has moved out of engagement with the load terminals 208, 210, keeping the circuit closed, and preventing arcing at the principal load line contacts 208, 210.

Within the bridging contact 206 and in electrical connection therewith, is a bi-metallic member 220 having a contact 221 thereon, said contact being adapted for cooperation with a contact 222 secured to an end of a bi-metallic element 223, which, as shown in Fig. 16, is secured at one end to the cap 200.

The bi-metallic member 220 normally lies in surface contact with the bridging contact 206 and, in the event the temperature of said contact

206 is raised by an overload condition, the increase in temperature is transmitted by conduction to the bi-metallic member 220. The unequal expansion of the components of the bi-metallic member 220 flexes it upwardly, as appears in dotted line in Fig. 14, to a position where its contact 221 engages the contact 222. Pursuant to an appropriate electrical connection, the closing of a circuit between contacts 221 and 222 energizes solenoid coil 203a, which attracts the armature 204 downwardly and causes the toggle spring 211 to snap the bridging contact 206 out of engagement with the load line contacts 208, 210, whereupon the subsequently following break between contacts 216 and 217 throws the circuit into open condition.

As is shown in Figs. 14 and 16, the cap 200 is provided with an aluminum inset 224 against a major portion of which the bi-metallic member 223 rests. The aluminum element 224 is subject to ambient temperature and transmits such temperature to the bi-metallic member 223, which moves closer to or away from the contact 221 according to whether or not said bi-metallic element 223 is heated or cooled.

When the bi-metallic element 223 moves toward the contact 221, as in the circumstance when the bi-metallic member 223 is cooled, the contact 221 has a lesser distance to move before striking against the contact 222, thereby affording means for compensating for variant ambient temperature and insuring that the circuit is broken only under pre-determined overload conditions.

As appears in Fig. 14, the solenoid coil housing 202, which is preferably of soft iron elements collectively providing opposed magnetic pole-pieces serving additionally as bearing guides for shafts 205, 218, is substantially smaller in diameter than the aluminum casing 201; the relatively large area of said casing 201 renders it effective to dissipate the heat generated by the solenoids during their brief periods of activity.

It is characteristic of the respective embodiments of the invention described herein that the reciprocating elements are of light weight, and that the toggle springs have positive positions of stable equilibrium sufficient to resist inertia-induced forces tending to throw the respective magnetic armature systems in one or another direction. It has been found in actual test, that an inertia force of 15 times the acceleration of gravity (15 G) is insufficient of itself to cause the circuit breaker to make or break circuit.

Whereas I have described my invention by reference to specific forms thereof, it will be understood that many changes and modifications may be made provided they do not depart from the scope of the claims.

I claim:

1. A circuit breaker comprising, in combination, switch means comprising spaced load-circuit contacts, a bridging contact for cooperation therewith in opening or closing said load-circuit, solenoid means for initiating movement of said bridging contact into open circuit position, an electric circuit for energizing said solenoid means, and a fixed contact and a movable contact in said solenoid energizing circuit, said movable contact including a bi-metallic element in surface engagement with an element of said switch means and movable toward said fixed contact upon rise in temperature of said switch means element whereby elevated temperature engendered in said switch means element by a predetermined overload condition causes said movable contact to

engage with said fixed contact to energize the said solenoid coil and open the load circuit.

2. In an electric circuit breaker, a pair of spaced fixed contacts in the circuit to be controlled, a bridging contact movable relatively thereto, solenoid means for moving said bridging contact into or out of engagement with said fixed contacts, the electric circuit of said solenoid means including a switch structure having a fixed contact, and a movable contact carried by an element movable toward or away from said fixed contact under the influence of temperature change in said movable element, said movable contact element being positioned in heat exchange relationship with said bridging contact to be sensible to the temperature thereof, whereupon a rise in temperature of said bridging contact beyond a predetermined value is effective to cause said solenoid circuit switch to close, to energize the solenoid to move the bridging contact away from the spaced fixed contacts.

3. In an electric circuit breaker having spaced, fixed contacts in the circuit to be controlled, a bridging contact to open or close the circuit thereacross, said bridging contact having a relatively large inturned flange, and a solenoid to cause said bridging contact to move into open circuit position; switch means in the energizing circuit of said solenoid comprising a fixed contact and a movable contact carried by a bi-metallic member confined within the inturned flange of said bridging contact and in heat exchange association therewith, said bi-metallic member being so constituted that upon a rise in temperature of said bridging member the contact carried by said bi-metallic member will close with the fixed contact of said solenoid circuit to energize the solenoid to move the bridging contact out of engagement with the spaced fixed contacts.

4. In an electrical circuit breaker, fixed load contact means; movable contact means cooperating with said load circuit contact means; "on" and "off" solenoid means for controlling said movable contact means; a casing enclosing said fixed load circuit contact means, said movable contact means and said solenoid means; thermostatic means disposed within said casing in heat exchange relation with said movable contact means; circuit means related to and controlled by said thermostatic means for energizing said "off" solenoid to disconnect said movable contact means with respect to said fixed load circuit contact means under predetermined temperatures arising under overload conditions under normal temperature conditions exteriorly of the casing; and thermostatic means carried by said casing responsive to temperature exteriorly of said casing and included in said "off" solenoid circuit means and cooperating with said first-named thermostatic means, whereby the electrical circuit breaker is opened under predetermined overload condition under joint temperature conditions interiorly and exteriorly of the casing of the circuit breaker.

5. An electrical circuit breaker under claim 4 wherein the thermostatic means responsive to temperature exteriorly of the casing is mounted within the casing and arranged to approach said first-named thermostatic means under temperature conditions exteriorly of the casing lower than normal temperature.
